[57] CLAIM

The ornamental design for a tire tread, as shown and described.

DESCRIPTION

FIG. 1 is a perspective view of a tire tread showing my new design, it being understood that a tread pattern is repeated over the outer circumference and shoulder of a tire, the opposite side being the same as that illustrated; and, FIG. 2 is a enlarged fragmentary front elevation view of the tread pattern of FIG. 1 showing my new design for the tire tread.

In the drawings, the dark stippled surface shading represents the recessed portion of the tread grooves, having a depth as best shown along the right edge of FIG. 1.

The broken line showing of a tire sidewall and inner bead is for illustrative purposes only and forms no part of the claimed design.
